(57) CLAIM

The ornamental design for a golf shoe outsole, as shown and described.

DESCRIPTION

FIG. 1 is a bottom perspective view of the golf shoe outsole of this invention;

FIG. 2 is a bottom plan view of the golf shoe outsole of this invention;

FIG. 3 is a medial side elevation view of the golf shoe outsole of this invention;

FIG. 4 is a lateral side elevation view of the golf shoe outsole of this invention;

FIG. 5 is a front elevation view of the golf shoe outsole of this invention;

FIG. 6 is a rear elevation view of the golf shoe outsole of this invention; and,

FIG. 7 is a top plan view of the golf shoe outsole of this invention.

The broken lines in FIGS. 1–7 depict the upper portion of the shoe, including laces and logo, which form no part of the claimed design. Also, the logo shown in broken lines on the bottom surface of the outsole forms no part of the claimed design.

1 Claim, 6 Drawing Sheets
